[57] ABSTRACT

A display system for dynamically exhibiting a plurality of advertising panels comprising a supply magazine and a track defining a U-shaped display path extending away from and returning to the magazine. The magazine is provided with a supply of panels which are sequentially moved from the storage area to a discharge station for engagement with the drive means for movement along the display path. Panels returning to the magazine are deposited in a receiving station and disengaged from the drive means for subsequent movement into the storage area. The panels are adapted for travel along the display path by carriers which also carry extending camming surfaces for contacting a panel in the receiving station and urging it into the storage area responsive to the movement of the panel entering the receiving station. This causes a corresponding shift of panels in the storage area and moves a panel from the storage area into the discharge station for engagement with the drive means and travel about the display path.

DYNAMIC ADVERTISING DISPLAY SYSTEM

BACKGROUND OF THE INVENTION

This invention relates to advertising displays and more particularly to an improved dynamic display system for exhibiting advertising signs.

In the field of advertising, the use of eye-catching signs is recognized as an effective way to convey information and to promote products. Typically, the advertising signs are artistically created and placed in strategic locations within a store, supermarket or the like, to be seen by as many persons as possible. The effectiveness of such advertising displays is increased by making the displays move, thereby to more readily attract attention.

An example of the dynamic display system, the general type to which the present invention relates, is shown in U.S. Pat. No. 3,735,513 granted May 29, 1973. In devices of this type, advertising signs are sequentially extracted from a magazine and moved in series along a path to an opposing magazine or returned to the same magazine for re-display. The magazine is provided with a discharge station where the sign is engaged with a drive means for travel along a track which defines the display path, and a receiving station where a sign is disengaged from the drive means. Within the magazines the signs not being displayed are stored in a stack and a cam-actuated pusher frame is provided to move the signs laterally through the magazine from the receiving station to the discharge station for recirculation along the display path. Display systems of this type are relatively noisy due to the mechanism required for shifting the signs in the stack and these systems can be difficult and expensive to maintain.

The present invention represents a substantial improvement over prior art dynamic display systems in that in operation it is quiet and mechanically reliable. The device is more economical to manufacture and maintain than dynamic display systems of the prior art.

Other features and advantages of the present invention will become apparent from the following detailed description, taken in conjunction with the accompanying drawings, which illustrate, by way of example, the principles of the invention.

SUMMARY OF THE INVENTION

The present invention provides an improved dynamic advertising display system wherein a large number of advertising signs can be sequentially displayed. The signs are stored in a magazine while not being displayed and improved means for automatically shifting the signs from a stored position to a position for engagement with a drive mechanism for travel along a display path are provided.

More specifically, the magazine is provided with a discharge station and a receiving station. A track extends from the discharge station, along the desired path of display to the receiving station. The receiving and discharge stations are spaced on opposite sides of the magazine and a sign storage area is interposed between the stations. In the presently preferred embodiment, a pair of spaced apart tracks extend laterally between the receiving station and the discharge station of the magazine for movably carrying the signs in the sign storage area. The lateral tracks communicate with the display

track so that a continuous path is provided for signs leaving the display track at the receiving station, moving across the sign storage area and entering the display track at the discharge station. Each display sign, which is preferably designed to depend downwardly from the display track, is provided with a camming surface along the edge adjacent the display track. The camming surface of a sign entering the receiving station contacts a corresponding camming surface of a sign in the receiving station to urge that sign out of the receiving station and into the sign storage area. A corresponding lateral movement of the signs in the storage area occurs and responsive to this movement, a sign is moved out of the storage area into the discharge station for eventual engagement with the drive means for movement along the display track.

In addition to the camming surface, each sign carries a pair of upstanding posts and casters for contact with the drive means and for movably supporting the sign along the display path and the lateral tracks in the sign storage area.

Further features of the present invention reside in the drive mechanism which is adapted for engaging the upstanding posts for movement along the display path; in the configuration of the display track; and in the mechanism in the magazine for causing engagement and disengagement of the drive mechanism and the signs. Other features and advantages of the display system of this invention will become apparent from the following detailed description, taken in conjunction with the accompanying drawings, which illustrate by way of example, the principles of the invention.

DESCRIPTION OF THE DRAWINGS

FIG. 1 is a perspective view, with portions broken away for economy of space, showing a dynamic advertising display system embodying the invention and showing advertising signs moving along a display path away from and towards a supply magazine.

FIG. 2 is an enlarged perspective view, partially broken away for economy of space, and partially in section, to show elements of the display path and drive means in engagement with an advertising sign.

FIG. 3 is an enlarged fragmentary sectional view taken along line 3-3 of FIG. 2.

FIG. 4 is an enlarged fragmentary perspective view of the magazine of FIG. 1 with portions cut away to show the receiving station and means for shifting signs in the magazine.

FIG. 4a is a fragmentary plan view of a sign entering the magazine and the camming action produced.

FIG. 5 is an enlarged fragmentary perspective view of one of the advertising signs of FIG. 1, partially cut away at the upper edge.

FIG. 6 is an enlarged sectional view taken along line 6-6 of FIG. 4.

FIG. 7 is an enlarged sectional view taken along line 7-7 of FIG. 4.

FIG. 8 is an enlarged fragmentary sectional view taken in the direction of line 8-8 of FIG. 4.

DETAILED DESCRIPTION

Referring to the drawings wherein like reference characters refer to like parts throughout the several figures, the present invention is embodied in a new and improved dynamic display system for displaying advertising panels 10 by movement of the panels 10 in series

from a magazine 11 along a display path shown generally as 12, returning to the magazine 11 for storage until ready for re-display. Such a system may be suspended from the ceiling in a supermarket, department store, or the like to present a repeating series of advertising messages in a conspicuous manner to customers in the store.

The system may be operated with two magazines, one at each end of a pair of display paths, although in the preferred embodiment it is preferred to employ a single magazine 11 and a continuous display path 12. The magazine 11 is provided with a discharge station 13 from which the panels 10 leave the magazine for display and a receiving station 14 in to which the panels 10 are moved after completing a circuit of the display path 12. Between the discharge station 13 and the receiving station 14 is a panel storage area 15 in which the panels 10 are movably stored prior to re-display.

The system also includes drive means for moving the panels 10 from the discharge station, along the display path 12 and for depositing the panels 10 in the receiving station 14. The panels 10, are automatically laterally shifted from the receiving station 14 into the panel storage area 15 and the panels 10 in the panel storage area 15 are laterally displaced causing a panel to be moved into the discharge station 13 responsive to the movement of a panel into the receiving station 14.

As is more specifically shown in FIGS. 1 and 4, the magazine 11 is a generally boxlike container of sufficient horizontal and vertical dimension to accommodate the panels 10 therein. The magazine 11 comprises an upper frame 16 which includes, an open ended U-shape channel 17 with its open ends in abutment with track sections 18 which are in communication with the display path 12. A pair of side panels 19, a rear panel, not shown, and a front panel 20 are affixed to the upper frame 16 by mounting brackets, not shown, to define the interior of the magazine 11, which comprises three areas, the discharge station 13, the panel storage area 15 and the receiving station 14. The front panel 20 is provided with a pair of vertically elongated, spaced apart slots 21 which are aligned with and define the exit of the discharge station 13 and the entrance to the receiving station 14.

A pair of spaced apart open ended tubular lateral tracks 22 are carried between track sections 18 for communication therewith. A longitudinal slot 23 extends along the bottom wall of each of the lateral tracks 22.

The magazine 11 is suspended from a ceiling, not shown, by suitable hangers 24.

The display path 12, is defined by an elongated tubular track 25 of rectangular cross-sectional configuration, having a discharge leg 26, a U-shaped leg 27 and a receiving leg 28 defining a continuous display path extending away from and returning to the magazine 11. The open ends of the track 25 at the discharge leg 26 and the receiving leg 28 abut against the open ends of the track sections 18 of the upper frame 16 for communication therebetween and are held in abutment by a member 29 comprising a channel 30 extending between the track legs and carrying a clamp 31 on each end for containing and clamping the ends of the track 25 and the open ends of the track sections 18.

As is more specifically shown in FIGS. 2, 6, 7 and 8, the interiors of the track 25, and the track sections 18, are separated in to an upper chamber 32 and a lower

chamber 33 by opposed inwardly extending flanges 34 whose inner edges define an upper slot 35 and whose upper surfaces define upper roller support surfaces 36. The bottom wall of the track 25 and the track sections 18 is provided with a longitudinal lower slot 37 and the inner surfaces of the bottom wall define lower roller support surfaces 38. A side wall of each of the track sections 18 is additionally provided with a pair of openings 39 which are aligned with the ends of the lateral tracks 22 and an arcuate slot 40 adjacent each of the openings 39 which extends from the lower slot 37 and communicates with the longitudinal slot 23 of the lateral track 22 for lateral movement of a panel out of the receiving station 14, across the panel storage area 15 and into the discharge station 13.

As is more specifically shown in FIGS. 1 and 2, a spaced apart pair of upstanding flanges 41, each having an inwardly turned lip 42, define a longitudinally running mounting channel extending along the upper surface of the track 25. Braces 43 extending between the receiving leg 28 and discharge leg 26 of the track 25 are affixed to the track 25 at the flanges 41 by a bolt 44 and a nut 45 for carrying the track while suspended from a ceiling by connection with the hangers 24 through a hook 46 and an eye bolt 47 carried by the brace 43.

For ease of shipping and the like, the receiving leg 28 and discharge leg 26 are comprised of an assembly of track sections. Assembly of the sections is facilitated by a spaced apart parallel running grooves 48 extending longitudinally along the bottom wall of the track 25. During assembly guide pins, not shown, are inserted in each of the grooves 48 at the point of abutment of the ends of the track sections to insure alignment of the upper slot 35 and lower slot 37 and alignment of the upper support surfaces 36 and the lower support surfaces 38 between sections. The sections are held together by brackets 49 overlying the abutting ends of the track sections and bolted to the flanges 41.

As best seen in FIGS. 2 and 5, each panel 10 is of generally rectangular configuration having a leading edge 50 in the direction of travel, a trailing edge 51 and a horizontally disposed upper edge 52. The panel 10 is carried at its upper edge 52 by an open ended tubular carrier 54 which is provided with a longitudinally running slot 55 in its bottom wall through which the panel 10 extends. The ends of the carrier 54 are substantially coterminous with the leading edge 50 and trailing edge 51 of the panel 10. A pair of spaced apart upstanding posts 56 are fixed on the upper surface of the carrier 54 for extension through the lower slot 37 of the track 25. The spacing between the posts 56 is equal to the spacing between the slots 23 of the lateral tracks 22 for alignment therewith in the receiving station 14. A support caster assembly 57 is journaled on the portion of each of the posts 56 extending through the slot of the track section 18 and the slot 23 of the lateral tracks 22 for movably supporting the carrier 54 along the lower rolling support surfaces 38 of the track 25 and track sections 18 and the lateral tracks 22. The upper end of the post 56 extends above the caster assembly 57 and is enlarged at 58 to retain the caster assembly 57 on the post 56. The caster assembly 57 is free to pivot about the post 56 on an axis normal to the axis of the rollers 59 of the caster assembly 57.

A camming cap 60 is affixed to each end of the carrier 54 for extension beyond the leading and trailing

edges, 50 and 51, of the panel 10. Each camming cap 60 is of substantially right triangular configuration with the base in abutment with the end of the carrier 54 and the hypotenuse defining a camming surface 61. The camming surface 61 of the camming cap 60 adjacent the leading edge 50 is faced inwardly in the direction of the interior of the magazine 11 and the camming surface 61 of the camming cap 60 adjacent the trailing edge 51 of the panel 10 is oppositely disposed.

As is most clearly seen in FIG. 4a, the camming surface 61 of the extending camming cap 60 of the carrier 54 entering the receiving station 14 contacts the camming surface 61' of the camming cap 60' on the trailing end of the carrier 54' which has been previously deposited therein. Responsive to the movement of the carrier 54 entering the receiving section 14, the camming surfaces 61 and 61' cooperate to impart a lateral movement to the carrier 54' urging the posts 56' of the carrier 54' out of the lower slot 37 through the arcuate slot 40 in to the slot 23 of the lateral tracks 22. The lateral motion of the carrier 54' also causes the caster assemblies 57' to swivel so that the rollers 59 are turned for movement through the openings 39 of the track sections 18 onto the lateral tracks 22. The carrier 54 is deposited in the receiving station 14 with the posts 56 in substantial alignment with the arcuate slots 40 for lateral movement of the carrier 54 upon the arrival of the next carrier in the series.

The lateral movement of carrier 54' out of the receiving station 14 and into the panel storage area 14 of magazine 11 causes a corresponding lateral movement of each of the carriers 54 and panels 10 in the panel storage area 15 and causes the carrier 54'' adjacent the discharge station 13 to be moved in a path defined by the arcuate slots 40 (FIG. 8) so that the posts 56'' of the carrier 54'' are in substantial alignment with the lower slot 37 of the track section 18 for engagement with the drive means and for travel along the display path 12. The caster assemblies 57'' are swiveled for travel of the rollers 59'' along the lower roller support surface 38 of the track section 18 and track 25.

The panels 10 are moved along the display path 12 by the drive means which engages the upper end of the post 56 of the carrier 54 nearest the leading edge 50. The drive means cooperate with the track sections 18 for engaging the post 56 in the discharge station 13 and for disengaging from the post 56 when the sign has been returned to the receiving station 14.

As illustrated in the drawings, an endless flexible cable 62 is trained around pulleys 63 which are journaled in a cross-member 64 carried by the U-shaped channel 17 of the upper frame 16 and around pulley 65 and drive sheave 66 journaled on a lateral member 67 carried by the U-shaped leg 27 of the track 25. A motor 68 is carried by the lateral member 67 and is drivingly coupled to the drive sheave 66. Adjusting screws 69 extend between L-shaped members 70 carried on the upper surface of lateral track 22 and lateral member 67 for adjusting the tension of the cable 62.

As more specifically shown in FIGS. 2 and 7, the pusher assemblies 71 are affixed in series along the cable 62. The spacing between the individual pusher assemblies 71 is equal to the desired spacing between individual panels 10 on the display path 12.

The pusher assembly 71 comprises an elongated vertically oriented body 72 affixed to the cable 62 by a clamping bracket 73. Extending downwardly from the

point of attachment, the body 72 defines a pusher bracket 74 comprising a pair of horizontal outwardly biased arms 75 for engaging the upper portion of the post 56. Extending upwardly from the point of attachment of the cable 62, the body 72 extends through the upper slot 35 and terminates in a rearward projection 76 formed adjacent the upper edge of the body 72. A pair of laterally projecting support rollers 77 are journaled in the upper portion of the body 72 to movably support the body 72 along the upper roller support surfaces 36 of the projecting flanges 34 responsive to the movement of the cable 62. The rearward projection 76 carries an elongated laterally projecting mounting 78 and a guide roller 79 is journaled adjacent each end of the mounting 78 for contact with the inner surfaces of the side walls of the track 25 to maintain proper orientation of the rollers 77, particularly when the pusher assembly is passing through the U-shaped leg 27 of the track 25 and the U-shaped channel 17 of the upper frame 16 of the magazine 11.

In operation, the post 56 nearest the leading edge 50 of the panel 10 is in engagement with the pusher bracket 74 of the pusher 71 for movement along the track 25. Upon return of the panel 10 to the receiving station 14 of the magazine 11, the pusher assembly 71 in cooperation with the track section 18 is elevated moving the pusher bracket 74 out of engagement with the post 56. In this manner the panel 10 and carrier 54 are deposited in the receiving station 14 with the posts 56 in substantial alignment with the open ends of the lateral tracks 22 for substantial lateral movement of the panel 10 into the panel storage area 15.

As best shown in FIGS. 6 and 7 a portion 80 of the upper roller support surface 36 is elevated adjacent the innermost opening 39 of track sections 18 so as to raise each pusher assembly 71 upwardly with respect to the lower support surface 38 to disengage the pusher bracket 74 from the post 56. In this manner the carrier 54 is deposited in the receiving station 14 with the posts 56 aligned with the arcuate slots 40 for lateral movement as has been described. Likewise, in the discharge station 13 (FIG. 7) the pusher assembly is raised over the post 56 and is returned to its normal elevation for engagement with the post 56. This is accomplished by removing the flanges 34 in the area adjacent the opening 39 and affixing a spaced apart pair of aligned ramps 81 to the opposing side walls of the track section 18, such as by bolts 82. The ends of the ramps 81 are in substantial abutment with the edges of the flanges 34 to provide an unbroken inclined upper support surface leading to and from the elevated portion 80.

To accommodate the raised position of the pusher assembly 71 while moving along the elevated portion 80 of the upper support surface 36 of the track section 18 in both the discharge station 13 and the receiving station 14, the upper wall of the track sections 18 is cut away over the elevated area 80 to allow the extension therethrough of a portion of the pusher assembly 71 while in the raised position (FIG. 6). The cable 62 is sufficiently flexible to be carried along with the pusher assembly 71 while passing over the ramps 81.

From the foregoing, it will be appreciated that the display system of the invention allows a large number of panels to be continuously exposed to view in a sequential manner and that the panels displayed may be of large size. Further the system is fully automatic. The panels 10 can be readily changed simply by removing

a camming cap 60 and inserting the upper edge 52 of a panel 10 into the interior of the carrier 54 with the panel depending downwardly from the carrier 54 through the slot 55.

While a particular form of the invention has been illustrated and described, it will be apparent that various modifications can be made without departing from the spirit and scope of the invention.

We claim:

1. A dynamic advertising display system comprising:

an enclosed storage magazine for holding a plurality of display panels in side by side relationship in a storage area and including a receiving station on one side of said storage area and a discharge station on the opposite side of said storage area and said magazine having means for lateral shifting of said panels from said receiving station to said storage area and from said storage area to said discharge station;

means defining a horizontal display path communicating with said discharge station and extending away therefrom and returning to said receiving station and communicating therewith, said display path including an elongated tubular track of rectangular configuration having a slot longitudinally running along the bottom wall thereof, the inner surfaces of the bottom wall adjacent said slot defining lower roller support surfaces, each side wall carrying an opposed aligned inwardly extending flange spaced above the bottom wall, said flanges separating said track interior into an upper chamber and a lower chamber, the inner edges of said flanges spaced apart to define an upper slot for communication between said lower chamber and said upper chamber and the upper surfaces of said flanges defining an upper roller of support surface;

means for carrying each of said panels along said display path and for shifting panels within said magazine, said means including an elongated carrier body from which each said panel depends, said carrier body provided with at least one upstanding post, a portion of which extends through said lower slot of said track and carries a caster assembly for travel along said lower roller support surface of said lower chamber, the ends of said carrier body defining a camming surface for contacting a carrier in said receiving chamber and laterally urging it out of said receiving chamber into said storage area and for concurrently shifting a carrier out of said storage area into said discharge station; and

drive means comprises a motor driven endless cable continuously circulating from said discharge station through said tubular track and to said receiving station, said cable carrying means cooperating with said track upper chamber for engaging said post of each said carrier in said discharge station for movement around said display path and for disengaging from said post said receiving station.

2. A dynamic advertising display system as defined in claim 1 wherein said elongated carrier body comprises an elongated open ended, rectangular tubular element provided with a longitudinally running slot along the bottom wall thereof through which a substantial portion of a panel carried therein extends, the ends of said tubular element being substantially coterminous with

the edges of said panel and each end carrying an extending right triangular shaped camming cap, the hypotenuse thereof defining a camming surface.

3. A dynamic advertising display system as defined in claim 2 wherein the edge of said panel in the direction of travel along said display path defines the leading edge and said camming cap extending beyond said leading edge is disposed so that said camming surface faces the interior of said magazine as said carrier enters said receiving station and said camming surface of said camming cap on the opposite end is disposed away from the interior of said magazine.

4. A dynamic advertising display system as defined in claim 1 wherein said drive means includes plurality of pusher assemblies carried by said endless cable, said pusher assemblies being spaced apart on said cable a distance substantially equal to the spacing between individual display panels on said display path, each said pusher assembly comprising an elongated vertically oriented body carrying on the lower end thereof, a pair of horizontally outwardly biased arms extending in the direction of travel defining a pusher bracket for engaging said upstanding post of said carrier, the upper portions of the body extending through said upper slot of said track and having a pair of laterally disposed support rollers journaled thereon for travel along said upper roller support surface of said track, the upper end of said body defining a rearward extending projection carrying a laterally extending member having journaled on each end thereof a guide roller, the axis of rotation of which is normal to the axes of rotation of said support rollers for guiding contact with the side walls of said track.

5. A dynamic advertising display system as defined in claim 1 wherein said magazine includes an upper frame member comprising a pair of spaced apart parallel running tubular track sections of rectangular configuration, each track section having an upper end lower chamber and the bottom walls of said upper and lower chamber each provided with longitudinally running slots and defining upper and lower roller support surfaces respectively, one end of each of said sections communicating with an end of said track defining said display path, at least one open ended tubular lateral track having a longitudinally running slot in the bottom wall extending between said track sections and in communication with the lower chamber of said track sections through an opening in the side wall of each of said track sections.

6. A dynamic advertising display system as defined in claim 5 wherein a pair of spaced apart parallel running lateral tracks defining forward and rear lateral tracks extend between said track sections and communicate therewith through a pair of aligned openings in the opposing side walls of each of said track sections.

7. A dynamic advertising display system as defined in claim 5 wherein said upper roller support surface of said track sections adjacent said opening defines a ramp for raising said pusher bracket out of engagement with said post of said carrier as said rollers of said pusher assembly pass over said ramp.

8. A dynamic advertising display system as defined in claim 7 wherein said ramp is positioned in each track section adjacent said aligned opening communicating with said rear lateral track.

9. A dynamic advertising display system as defined in claim 1 wherein said means defining a display path

communicate with said discharge station of a first magazine and extend to and communicate with said receiving station of a second magazine and communicate with said discharge station of said second magazine and extend to and communicate with said receiving station of said first magazine.

10. A dynamic advertising display system as defined

in claim 1 wherein said display path defines a U-shaped path having a discharge leg communicating with said discharge station of said magazine and a receiving leg communicating with said receiving station of said magazine.
